United States Patent Office

Des. 195,787
Patented July 30, 1963

195,787

COMBINED BOTTLE AND CLOSURE

Robert B. Thompson, Overland Park, Kans., assignor to
Faultless Starch Company, Kansas City, Mo., a corpora-
tion of Missouri

Filed Aug. 20, 1962, Ser. No. 71,372

Term of patent 14 years

(Cl. D58—8)

Fig. 1.

Fig. 2.

Fig. 3.

FIG. 1 is a front elevational view of a combined bottle and closure embodying my new design;

FIG. 2 is a side elevational view of same with the upper portion broken away to show the closure in cross-section; and

FIG. 3 is a top plan view of same.

I claim:

The ornamental design for a combined bottle and closure, as shown.
